UNITED STATES PATENT OFFICE.

JACOB STEBE, OF CHICAGO, ILLINOIS.

DESIGN FOR A STRAW-WEAVE AS APPLIED TO A STRAW HAT.

58,950.

Specification for Design.

Patented Sept. 6, 1921.

Application filed October 14, 1920. Serial No. 417,059. Term of patent 3½ years.

To all whom it may concern:

Be it known that I, JACOB STEBE, a citizen of the United States, residing at Chicago, in the county of Cook and State of Illinois, have invented a new, original, and ornamental Design for a Straw Weave as Applied to a Straw Hat, of which the following is a specification, reference being had to the accompanying drawing, forming part thereof.

The new and ornamental design herein shown as applied to a straw hat resides in the particular type of weave wherein the straw is woven in winding units which are tied together on uniformly spaced radial

lines, portions of certain of the units being interwoven and overlapped on adjacent units at uniform distances apart and said portions being angularly disposed to the winding units and overlapping the radial tying lines.

Figure 1 is a plan view of a hat embodying my new ornamental design for a straw weave.

Fig. 2 illustrates a side elevation of same.

I claim:

The ornamental design for a straw weave as applied to a straw hat, as shown and described.

JACOB STEBE.
